CARBURETOR CONTROL DEVICE

Hugh Rodman, Chicago, Ill.

Application April 24, 1933, Serial No. 667,758

6 Claims. (Cl. 192—.01)

My present invention, in its broad aspect, has to do with the provision of means for automatically controlling the operation of the carburetor of a motor vehicle, and the consequent nature of the resulting combustible charge delivered to the cylinders. More particularly it is my purpose to provide an actuating piston and cylinder or bellows assembly in conjunction with an accelerator of an automobile (or other) motor which is inter- 5
 polated in a vacuum line associated with the intake manifold of the motor, and with certain control devices in conjunction with the speedometer and brake or clutch, thereby to automatically control the formation of the combustible charge 10
 10 through the carburetor to conform with the speed of the motor and the circumstances of its operation.
 15

In attaining the various ends and objects of my invention, I provide in conjunction with the accelerator and carburetor throttle rod a piston and cylinder assembly. Associated with the cylinder is a vacuum line tapped into the intake manifold so that under ordinary circumstances the suction 20
 in the intake manifold will operate through the vacuum line and cylinder to actuate the piston, which in turn operates the accelerator and throttle actuating rod of the carburetor. However; I have provided means whereby the suction developed in the vacuum line is automatically 25
 30 controlled thereby to make the operation of the accelerator and carburetor dependent upon certain conditions of operation of the motor vehicle. These means include an automatic control device associated with the speedometer or actuating mechanism similar to a speedometer whereby 35
 more or less air is admitted to the vacuum line dependent upon the speed of the vehicle, and included in said control device associated with the speedometer is a manual control dial arranged on 40
 the instrument board for setting the automatic control to be effective at certain predetermined speeds. I also provide an electrically operated device in conjunction with the clutch or brake pedal for controlling admission of air to the vacuum line, and there is a manually adjustable control valve at the intake manifold to regulate the effectiveness of the same on the vacuum line. It 45
 is pointed out, of course, that the pressure or effective force of the vacuum line is dependent 50
 55 on the extent of vacuum created, which in turn is dependent upon the amount of outside air admitted thereto to counteract the suction action of the intake manifold.

The control device can be mounted on any type of speedometer or tachometer, and since either

is directly associated with the drive shaft the engine speed is regulated with relation to the car speed. Therefore on a car equipped with free wheeling; if the car is coasting down a hill and is going at a greater speed than the predetermined 5
 set speed, the throttle valve will be closed and the motor idling. As the car loses speed on the level it will come back to the set speed and the automatic control will then be effective to open the valve enough to hold the car at its set speed. The 10
 setting is accomplished by the aforementioned manual dial on the instrument board which is calibrated in miles per hour and geared to the vacuum tube holder in the control to adjust the 15
 same after the manner which will be hereinafter described in greater detail.

My invention also contemplates the provision of a unique control mechanism for use in conjunction with the speedometer; this includes means whereby the admission of air to the vacuum line is not only regulated by the car speed, 20
 but also manually by setting at predetermined effective speeds.

My device is effective and simple in construction and may be used either with or without free wheeling, and with any conventional form of speedometer or carburetor; and it is effective in attaining better regulation of the combustible charge to the end that motor operation is improved and a saving effected in the gasoline consumption. Other and equally important advantages will be apparent as the description proceeds, 25
 but interpretation of the invention should be 30
 made in the light of the claims.

In the drawings wherein is illustrated the preferred form of my invention:— 35

Figure 1 is a diagrammatic or schematic view of my control device and system applied to the conventional parts of a motor vehicle;

Figure 2 is a simplified form thereof; 40

Figure 3 is a front elevation of my control device associated with the speedometer;

Figure 4 is a fragmentary perspective view of the gear mechanism for manually setting the position of the vacuum line; 45

Figure 5 is a top plan view of my control device associated with a speedometer;

Figure 6 is a detail view of the vane used to control intake of air to the vacuum line;

Figure 7 shows transverse views (A and B) of the types of orifices preferred for admission of air to the vacuum line; and 50

Figure 8 is a view of the cam wire used to actuate the air control vane in conformity with the speedometer reading. 55

Figure 9 is a diagrammatic view of the valve control mechanism associated with the brake and clutch pedals.

Figure 9A is a sectional view through the fitting and valve on the intake manifold.

In the drawings, like characters of reference refer to like or similar parts throughout the several views.

10 Referring now particularly to Figure 1; the numeral 1 designates the intake manifold of a conventional motor power plant, and 2 the carburetor. The accelerator pedal is designated 3; the brake pedal 4 or the clutch pedal and the conventional speedometer by 5, while the carburetor or throttle control rod is shown at 6. 15 All of these parts are conventional and form no part of my present invention.

In carrying my invention into effect, I provide a main vacuum line (or pipe) designated 7 which 20 communicates with the intake manifold 1 through a fitting 8 having a suitable form of manual regulating valve 9. One end of the vacuum line communicates with a cylinder 10 having a piston 11 working therein, and the other end has 25 branches 12 and 13; respectively leading to the speedometer 5 and to valve control mechanism 14 associated with the brake or clutch pedal 4. Branches 12 and 13 are respectively intakes for 30 air, and their effective regulation controls the influence of the intake manifold upon the vacuum line and the piston 11 in cylinder 10. That is, the maximum effectiveness of the suction action of the intake manifold on the vacuum line 35 is when both branches 12 and 13 are closed, in which event the entire suction action is directed to the cylinder 10 and piston 11 with the result that the piston will be drawn forward and the accelerator pedal down. As the quantity of air admitted either to branches 12 and 13 increases, 40 the effective action of the intake manifold suction is reduced in the vacuum line and cylinder 10 until the minimum effectiveness of the influence of the suction in the intake manifold is reached when either (or both) branches 12 and 13 are 45 fully open, at which point the accelerator pedal is at its normal inoperative position and the motor idling.

In order to attain effective and largely automatic control of the carburetor I provide means in conjunction with the brake or clutch pedal which includes a valve 15 normally latched in a closed position so that branch 18 is normally held closed when the brake or clutch is in inoperative position. The latch designated 16 is pivoted at 55 16a and is T-shaped, with one arm engaged by spring 17 to normally press on the valve stem 18 to force the valve in closed position against the action of spring 19; the other arm of the latch is engaged by a solenoid 20 which in turn is energized from a switch 21 arranged to be actuated, after the manner shown in Figure 9, by the actuation of either the brake pedal 4 or the clutch pedal so that when pressure is applied to either, the switch 21 having battery connections 21a 60 65 will be closed to energize the solenoid, which in turn will throw the latch and the valve will be forced open by the spring 19. The switch 21, as shown in Figure 9, is of a conventional form having a spring pressed button engaged by the 70 brake pedal 4, or the clutch pedal as the case may be, to be operative through the instrumentality of the brake or the clutch pedal. Accordingly, when the brake and clutch pedals are depressed the vacuum line effectiveness is neutralized, and 75 the car is under conventional control; i. e. the

accelerator must be pressed to feed gas to the carburetor. If, however, it is not necessary to press the clutch as in some improved forms of vehicle control or where neither the brake nor clutch pedals are depressed, the branch 13 is closed, and my invention becomes effective. Accordingly it may be said that branch 13 is effective to neutralize the action of my vacuum control of the carburetor when the brake and clutch are in operation—in which case the car is under standard control through the accelerator foot pedal. 5 10

A simplified control of branch 13 is shown in Figure 2 in which a foot button 22 having a spring 22a to hold it in normal position is utilized to actuate valve 22b in casing 22c to close branch 13.

Assuming now that neither the brake is actuated nor clutch disengaged, that is the car is simply running along in the usual manner in transit. In this case control of the vacuum is through branch 12 in the manner which will now be described.

Branch 12 extends in proximity with the speedometer 5 where it terminates in an L-shaped tube connection 23 mounted on the plate 24 extending from the speedometer housing. The plate 24 has a pair of brackets 25 each carrying an adjustable bearing element 26. Between the bearing elements 26 is mounted a shaft 27 carrying an annular plate or disc 28 and a gear 29; the vacuum tube connection 23 is mounted on both the disc 28 and gear 29, and the gear 29 is engaged by a pinion 30 on a shaft 31 leading to a calibrated dial 32 on the instrument board. These parts are shown in detail in Figures 3, 4, and 5. The dial is calibrated in miles per hour, and by turning the dial the position of the vacuum tube connection 23 can be adjusted on a radius having the shaft 27 as a center. The plate 24 also has another set of brackets 33 carrying adjustable bearing elements 34 in which is mounted a shaft 35. The axis of rotation of the shaft 35 is the same as the axis of rotation of the shaft 27. On the shaft 35 is mounted a vane 36 and a hair spring 37. The vane 36 swings in the same plane as the orifice 23a at the end of the vacuum tube connection 23. This orifice may be slightly flattened or otherwise as shown in views A and B of Figure 7. The vane has a pin or stop 38 on its surface facing the orifice and this surface is preferably ground to form a closure over the orifice, either partial or complete depending on the position of the vane with respect to the orifice in the vacuum tube connection. The shank or standard 39 of the vane is partially screwthreaded to carry a counterbalancing weight 40, and on the lower end thereof is a pin 41. The pin 41 rides inside of a wire cam 42 which is mounted on the post 43 of the speedometer to move when the reading on the speedometer dial changes. The cam is formed of wire and is of the type giving a regularly increased angular velocity—for instance an Archimedes cam has been found satisfactory. The hair spring 37 serves to move the shaft 35 to so position the vane that the pin 41 at all times engages the inner face of the cam. There is provided an adjusting arm 44 for the hair spring 37. By this means when the readings on the speedometer increase the cam is moved to throw the vane to gradually uncover the orifice in the vacuum tube connection. The setting of the control mechanism is effected by manually adjusting the position of the vacuum tube connection by means of

the dial 32 so that the automatic control through the instrumentality of the vane may be set to be effective at a certain definite number of miles per hour.

5 The operation of my control is as follows;— Assuming that a car is coasting down a hill, and by reason of free-wheeling the vehicle has a greater speed than the engine speed; the throttle valve being shut off the engine will idle. As the 10 vehicle loses speed on the level it will come back to the set speed in which case the control will come into action and open the throttle valve enough to hold the car at set speed. The setting is accomplished by means of the dial 32 15 which is set at the desired number of miles per hour, and the stop 38 lies against the side of the orifice when the speed is set and when the car speed is lower than the engine speed. When the car speed reaches the engine speed or set speed 20 the cam engages the pin and the vane is moved over the mouth of the orifice thereby letting in air, thereby in turn permitting the throttle to close enough to bring the car to set speed. Explaining now the operation with respect to the 25 several parts. The dial 32 is turned to fix the set speed at so many miles per hour. This setting of the dial 32 moves the vacuum tube connection 23 through instrumentality of pinion 30 and gear 29 and the movement of the vacuum tube connection in turn causes the wall of the orifice 23a to engage the stop 38 on the vane 36 so that the vane and the orifice are aligned with each other and no air is admitted through the orifice into the vacuum tube connection. In this case the 30 pin 41 at the end of the vane is slightly moved away from the cam 42. The cam will not engage the pin again until the speedometer reading is equivalent to the miles-per-hour (set speed) reading of the dial 32; when the speedometer 35 reading reaches or passes the dial reading the pin 41 is re-engaged with the cam and the vane moved away from the orifice to let in air to the vacuum line.

From the foregoing it is believed that the operation and construction of my invention will be apparent, but since changes may be made in details to conform to varying conditions of practice, without departing from my inventive concept, emphasis is again laid upon the fact that 45 interpretation of the scope of my invention should only be conclusive when made in the light of the subjoined claims.

I claim;—

1. The combination in a motor vehicle and power plant assembly, a cylinder and piston unit connected with the accelerator, a vacuum line communicating with the cylinder and with the intake manifold, and having branch connections leading to the speedometer and to a relief valve, 55 means in conjunction with the brake for controlling the relief valve to admit air to the vacuum line when the brake is pressed, and means in conjunction with the speedometer for automatically admitting air to the vacuum line when 60 certain predetermined speeds are reached.

2. The combination in a motor vehicle and power plant assembly, a cylinder and piston unit connected with the accelerator, a vacuum line communicating with the cylinder and intake 65 manifold to actuate the accelerator upon increase of suction in the vacuum line, a valve

in the vacuum line, means connecting the valve with the clutch to open the valve when the clutch is actuated, and a control device in the vacuum line connected with the speedometer whereby when the speedometer readings vary, more or less air will be admitted to the vacuum line. 5

3. The combination in a motor vehicle and power plant assembly, a cylinder and piston unit connected with the accelerator and carburetor, a vacuum line communicating with the cylinder and intake manifold to actuate the accelerator and throttle of the carburetor upon increase of suction in the vacuum line, a valve in the vacuum line, means for normally holding the valve closed, means connected with the brake for opening the valve, and a control device in the vacuum line having a valve device for admitting air to the vacuum line as the speedometer reading increases. 10 15

4. The combination in a motor vehicle and power plant assembly, a cylinder and piston unit connected with the accelerator, a vacuum line communicating with the cylinder and intake manifold to actuate the accelerator upon increase of suction in the vacuum line, a valve in the vacuum line, means connecting the valve with the clutch to open the valve when the clutch is actuated, a control device in the vacuum line connected with the speedometer whereby when the speedometer readings vary, more or less air 20 25 will be admitted to the vacuum line, and means for setting the control device so that it will be ineffective except at certain predetermined speeds of the speedometer.

5. The combination with the intake manifold, 35 carburetor and speedometer of a motor vehicle, a vacuum line communicating with the intake manifold and having a pressure responsive device interpolated therein and connected with the carburetor to regulate the explosive charge, and 40 a control device in the vacuum line and connected with the speedometer; said control device comprising an opening in the vacuum line, and a vane movable to open or close the opening, a cam connected with the speedometer, and means 45 on the vane engaging the cam to adjust the vane and the admission of air to the vacuum line in accordance with the reading on the speedometer.

6. The combination with the intake manifold, carburetor and speedometer of a motor vehicle, 50 a vacuum line communicating with the intake manifold and having a pressure responsive device interpolated therein and connected with the carburetor to regulate the explosive charge, and a control device in the vacuum line and connected with the speedometer; said control device comprising an opening in the vacuum line, and a valve mechanism controlling admission of air to the opening, a cam associated with the speedometer, and means connected with the valve and 55 engaging the cam so that the valve will be actuated in accordance with the movements of the speedometer, and setting means including an adjustable mounting for the vacuum line adjacent the opening therein, and manually operated to 60 adjust the position of the vacuum line with respect to the valve device to cause the same to function upon predetermined speed readings on the speedometer. 65
